UNITED STATES PATENT OFFICE.

JOHN D. RAUCH, OF LIMA, OHIO, ASSIGNOR TO THE OHIO STEAM SHOVEL COMPANY, OF LIMA, OHIO, A CORPORATION OF OHIO.

POWER SHOVEL.

Application filed March 2, 1925. Serial No. 12,476.

To all whom it may concern:

Be it known that I, JOHN D. RAUCH, a citizen of the United States of America, and a resident of Lima, in the county of Allen 5 and State of Ohio, have invented a certain new and useful Improvement in Power Shovels, of which the following is a specification.

This invention relates to improvements 10 in power shovels. The principal object of my invention is to provide a simple, durable and efficient mechanism for operating the hoisting drums, dipper operating devices, turn-table and propelling devices.

15 The invention will best be understood by reference to the accompanying drawings, in which—

Figure 1 is a view in side elevation of a power shovel constructed in accordance with 20 my invention.

Figure 2 is an enlarged plan view of the platform of the shovel, showing the mechanism thereon.

Figure 3 is an enlarged front view of the 25 shovel shown in Fig. 1, but with the dipper and boom removed.

Figure 4 is a detailed view in part cross section of the main drive gear and reversing mechanism.

30 Figure 5 is a detail in part section of the dipper handle operating mechanism on the boom.

Figure 6 is a side view in part section of the dipper handle operating drum shown 35 in Fig. 5.

Figures 7 and 8 are detailed views of the change speed transmission mechanism.

Figure 9 is a view in cross-section of the 40 reversing planetary transmission for the dipper handle operating mechanism.

Referring now to details shown in the drawings, my invention is illustrated as applied to a power shovel having the motor and main operating mechanism carried on a 45 frame 1, which frame is pivotally mounted to swing on a vertical axis upon a base 2. The base 2 is provided with propelling mechanism of any suitable form, herein consisting of an endless tread mechanism 3.

50 The shovel 4 is of an ordinary dipper type having a handle 5 provided with a rack 6, engaging a pinion 7 carried on a boom 8, the latter being arranged at the front end of the main frame but so as to be raised or lowered by suitable draft means, such as a

cable 10, suitably controlled from the main frame. The dipper 4 is further connected for operation by means of a single cable 11 passing over a sheave 12 on the upper end of the boom 8 and wound upon a main 60 operating drum 13.

The driving motor 20 is of the usual multi-cylinder hydrocarbon type mounted on a transverse axis at the rear end of the main frame 1. The main drive shaft 21 of this 65 motor is connected through a pinion 19 and reach gear 22 to a gear 23 on a shaft 24 also arranged on a transverse axis but in front of the motor. The main cable drum 13 is arranged substantially in the center 70 of the frame 1 in front of the motor and is loosely mounted on a transverse shaft 28, said shaft having bearing in longitudinally disposed supporting frame members 29 and 30, extending forwardly from the motor 20. 75

The driving connection between the shaft 24 and the drum 13 is afforded through a pinion 31 on shaft 24, a gear 32 keyed on the shaft 28 concentric with the drum 13 and meshed with a gear 35 forming one part 80 of a friction clutch device 36 forwardly of the drum 13. Details of this friction clutch device are clearly shown in Fig. 4 from which it will be seen that a driven member 37 is keyed on shaft 38, adjacent the loosely 85 mounted driving gear 35. A friction band consisting of a circular part 39 surrounds a drum 37a on said driven member, one end of said band being connected with a lever 40a on one of the rocking shafts 40 extending through the driving gear 35 and the other end being connected direct to said rocking shaft. The intermediate portion of the friction band 39 is supported by a loop 39a on the opposite shaft 40. The rocking shafts 90 95 40, 40 are actuated to tighten or loosen the friction band by a sliding clutch collar 41 mounted on the shaft 38 and connected by links 42, 42 and levers 43, 43, as shown in Figure 4. A pinion 45 is carried on an extended hub 44 of the driven member 37, and is meshed with a gear 46 mounted rigid with the drum 13 for driving the latter.

An independently operated brake band 48 is also mounted in frictional engagement 100 with the member 37 to control the unwinding of the cable from the drum 13.

From the above description it will be seen that I provide a train of gearing in which the desired gear reduction is provided and 110

in which a friction clutch is included so as to permit flexibility of operation, which is especially desirable when a hydrocarbon motor is used, as a prime mover.

5 Mechanism is also provided in connection with the driving mechanism just described for operating the swinging movement of the main frame 1 with respect to the base 2 and also for operating and propelling the device. This latter mechanism includes both reversing device and a change speed transmission, inasmuch as it is desirable to perform both the turning movement and the propelling movement of the shovel in either 10 direction and at varying rates of speed. The reversing mechanism is located at one side of the power drum 13 and is driven from the extended end of the shaft 28 upon which said drum is loosely mounted. This 15 shaft, as has been above described, is positively driven through gears 22, 23, shaft 24 and gears 31 and 32, the latter gear being keyed on the shaft 28. The reversing mechanism comprises a pair of oppositely disposed friction clutches 50 and 51, which may be similar in construction to that described in connection with the clutch 36, each comprising a driving member 52 and a driven member 53 having a miter gear 54, loosely 20 mounted on the shaft 28. The two miter gears are both meshed with a beveled pinion 54^a carried on a shaft 55 having bearing in the change speed transmission housing 56 mounted forwardly of the reversing mechanism just described. The clutches 50 and 51 are controlled through a pair of shifter members 60 and 61 interlocked in the usual manner so as to throw the coating clutch elements of one of the clutch members into 25 engagement when the other clutch is disengaged, and vice versa, thus causing one or the other of the miter gears 54 to afford a positive driving connection to the miter gear 54^a so as to drive the latter in one direction or the other, as desired. A neutral position of the clutch members is also provided in which neither of the gears is driven.

The change speed transmission device is located in the casing 56 and provides two 30 driving connections at the forward end thereof, as will now be described. A sliding gear 57 is feathered on shaft 55, to be shifted by yoke 57^a and a connected rack 57^b and pinion 57^c suitably mounted on the 35 top of the casing 56. The sliding gear 57 may be meshed with gear 58 keyed on shaft 58^a extending through the forward end of casing 56 and having a bevelled gear 65 thereon. The latter gear is connected with 40 a bevelled gear 66 on a vertically disposed shaft 67 having a pinion 68 at the lower end of said shaft below the frame 1 and engaged with a toothed periphery 69 carried on the base 2 so as to rotate the frame 1 45 with respect to the base 2 under power of

the motor. A series of rollers 70, 70 of the usual form are carried on the main frame 1 and engage an annular track 71 on the base 2, so as to reduce the friction as the frame is 70 rotated.

The second driving connection from the gear 57 in transmission housing 56 is provided by meshing said gear with a gear 59 keyed on shaft 60. The latter shaft extends through the forward end of casing 56 and 75 is provided with a beveled driving pinion 75 meshed with a pinion 76 on a transverse shaft 77. A beveled pinion 78 is keyed on the inner end of the shaft 77 and is meshed with the beveled pinion 79 on a vertical 80 shaft 80 arranged concentrically of the vertically turning axis of the frame 1 upon the base 2 so as to afford a driving connection between the motor and the propelling means carried by the base 2. An increased speed 85 connection may also be provided between sliding gear 57 and driving gear 75, by shifting the sliding gear further into engagement with a gear 61 loosely mounted on shaft 58^a and meshed with a smaller gear 90 90 keyed on shaft 60 adjacent gear 59. This affords a driving connection to the propelling devices at an increased speed and in a direction reversed from the drive through gear 59. Any suitable well known form of propelling device may be provided on the base, such as the endless tread mechanism 3, as shown. The construction of the latter need not be described in detail as it forms 95 no part of the present invention. 100

I also provide means for controlling the movement of the dipper handle, through the rack 6 and the pinion 7. In the form shown this means comprises a drum 90 arranged on a shaft 91 transversely of the front end of the main frame 1. A clutch 93 of the friction type hereinbefore described, is adapted to provide a driving engagement between the drum 90 and the gear 94 concentric therewith, this gear being meshed as shown, to the driving gear 35 associated with the clutch mechanism 36 intermediate the drum 90 and the main drum 13. The drum 90 is also provided with reverse driving connections, comprising a gear 95 keyed on shaft 91 to rotate with the driving gear 94, and meshed with a plurality of planetary gears 98, 98 carried on a rotatable member 97. The outer peripheries of the planetary gears engage an internal gear 98^a on the drum 90 member 96 integral with the drum 90. 110

A friction band 96 engages the drum 96 to provide braking action thereon. A similar friction band 97^a restrains rotation of the planetary member 97 when it is desired to 115 effectuate the driving connection through gears 98 in the usual manner, thus reversing the direction of rotation.

A flexible cable 99 is wound upon the drum 90. The two ends of the cable extend 120

- forwardly and downwardly over the idler pulleys 100 mounted on the boom 8 adjacent its point of pivotal connection with the frame 1 and from thence the ends of the cable extend upwardly and are wound about a drum 101 carried on the boom adjacent the pinion 7. The drum 101 is provided with a gear 102 thereon (see Fig. 5) engaging a gear 103 which rotates the rack 7.
- 10 From the above description it will be seen that by rotating the drum 90 in either direction, the pinion 7 may be rotated so as to force the rack 6 and dipper handle 5 inwardly or outwardly as required. Furthermore, the brake band 96^a may be operated so as to maintain the dipper handle in any desired position.

Means are also provided for adjusting the tension of the cable 99 upon drums 90 and 101. In the form shown, both of said drums are provided with helical grooves 110 in which the cable 99 is wound in the usual manner.

Referring now to the drum 101, which is best shown in cross section in Fig. 5, it will be seen that I provide means whereby the drum body is split on a transverse plane, so as to provide two portions 111 and 112 at opposite ends thereof. These portions are loosely mounted on sleeves 111^a and 112^a respectively, both being keyed on the shaft 98. The gear 102 is also keyed to rotate as a unit with the shaft 98 and sleeves 111^a and 112^a. The sleeves 111^a and 112^a each have worm gears 113 at their outer ends, engaging the toothed periphery 113^b of the adjacent drum portion. This arrangement permits either drum portion to be turned separately in either direction with respect to the shaft 98 by applying a crank of the usual kind on the squared end 113^b of either of the worms 113. The ends of cable 99 being connected respectively to the two portions 111 and 112, the tension on the rope may thus be adjusted as desired.

The arrangement of gearing hereinbefore described, is especially advantageous in connection with a single line shovel of the type herein disclosed, that is to say, the type of shovel wherein the dipper is connected directly to the cable drum 15 instead of having its cable doubled back upon itself one or more times over pulleys so as to produce a double or quadruple connection between the boom and the dipper. Such single-line shovels have certain structural and operating advantages over other types of power shovels, but on account of the direct connection to the dipper as aforesaid, the main operating drum 13 is under considerably more direct stress during operation than is the case of the more usual arrangement of cables connected to the dipper through double or quadruple pulley connections. Consequently, there is considerably more stress

upon friction driving clutches and brake devices used for controlling a single-line drum, and under ordinary conditions it has proved quite difficult to provide braking devices and friction clutch devices of ordinary size and strength which will stand up satisfactorily under ordinary working conditions. In applicant's device, it will be observed that the friction clutch 36 and friction brake band 39 are mounted on a separate rotating member in front of the main drum 13 and are operatively connected thereto through a gear reduction, thus making it possible to provide a friction clutch and a friction brake of the usual size, and yet of sufficient strength to drive and control said drum satisfactorily.

It will further be observed that owing to the single-line cable connection as above described, it is not necessary to provide such a large drum as in the usual case of pulley connected devices, consequently with the construction shown, the drum 13 is more compact than usual and it is practical to provide a particularly compact arrangement wherein the reversing mechanism and change speed mechanism are located at one side of the drums.

Among other advantages of a device constructed as above described is the arrangement of the drum 13, clutch and brake device 36 and drum 90 in longitudinal alignment with each other in front of the motor and between the main supports 29 and 30 arranged centrally of the frame 1. The driving gears 30, 32 and 35 thus extend in a general line forwardly from the motor to the friction clutch and frictional brake device 36, and the direction of driving connections to the drum 13 is then reversed through the gears 45 and 46 to the drum, while the driving connections to the drum 90 extend forwardly from gear 35 to gear 44, thus providing an especially compact and simple arrangement of driving connections.

The reversing mechanism and change speed transmission housing are both located on one side of the centrally disposed line of drums and gearing, thus leaving the other side of the platform on the main frame clear for the operator, so that he may pass readily from his controlling station at the front end of the platform along the side of the drums and gearing, and to the motor at the rear end for ready access to these parts for observation, readjustment or repair.

I claim as my invention:

1. In a device of the class described, a frame having a boom and a dipper on the forward end thereof, a motor at the rear end of said frame, flexible cable controlling means for said dipper including a drum mounted on a transverse axis in front of said motor and operatively connected to the

latter through friction clutch means rotatable on an axis in front of said drum, gear reduction mechanism interposed between said clutch and said drum, and brake means associated with said friction clutch means.

2. In a device of the class described, a frame having a boom and a dipper at the forward end thereof, a motor at the rear end of said frame, flexible cable controlling means comprising a single line cable extending between said dipper and a drum mounted forwardly of said motor on a transverse axis, and power connections between said motor and said drum including friction clutch means rotatable on an axis forwardly of said drum, and a reduction gear connection between said last named means and said drum.

3. In a device of the class described, a frame having a boom and a dipper at the forward end thereof, a motor at the rear end of said frame, flexible cable controlling means comprising a single line cable extending between said dipper and a drum mounted forwardly of said motor on a transverse axis, and power connections between said motor and said drum including brake means rotatable on an axis forwardly of said drum and a reduction gear connection between said last named means and said drum.

4. In a device of the class described, a frame having a boom and a dipper at the forward end thereof, a motor at the rear end of said frame, flexible cable controlling means comprising a single line cable extending between said dipper and a drum mounted forwardly of said motor on a transverse axis, and power connections between said motor and said drum including friction clutch means and brake means rotatable on an axis forwardly of said drum, and a reduction gear connection between said last named means and said drum.

5. In a device of the class described, a frame having a boom mounted at the forward end thereof, a dipper provided with a handle having a rack and pinion connection with said boom, a hydrocarbon motor at the rear end of said frame, flexible cable means connected to said dipper and extending over a sheave carried by said boom, a drum for said cable means mounted forwardly of said motor, a second drum at the front of said frame provided with flexible draft connection with said rack and pinion means to drive said means in opposite directions, and reversible power connection for said last named means.

6. In a device of the class described a frame having a boom mounted at the forward end thereof, a dipper provided with a handle having a rack and pinion engagement on said boom, a motor at the rear end of said frame, a single line flexible cable connected between said dipper and extend-

ing over a sheave carried by said boom, a drum for said cable means mounted forwardly of said motor, a second drum at the front end of said frame and provided with flexible draft means having connection with said rack and pinion means on the boom, friction clutch means rotatable on a transverse axis between said drums and affording selective driving connection with the first named drum through gear reduction means, an independent friction clutch device concentric with the second drum for controlling rotation of the latter.

7. In a device of the class described a frame having a boom mounted at the forward end thereof, a dipper provided with a handle having a rack and pinion engagement on said boom, a motor at the rear end of said frame, flexible cable means connected to said dipper and extending over a sheave carried by said boom, a drum for said cable means mounted forwardly of said motor, a second drum at the front end of said frame and provided with flexible draft having connection with said rack and pinion means on the boom, friction clutch means rotatable on a transverse axis between said drums and affording selective driving connection with the first named drum, an independent friction clutch device concentric with the second drum for controlling rotation of the latter, and planetary reversing mechanism effective for driving said last named drum.

8. In a device of the class described, a base, a frame pivotally mounted on said base to swing in a horizontal plane, a boom and dipper mounted at the forward end of said frame, motor at the rear end of said frame, flexible cable means for said dipper comprising a single line cable connected with a drum mounted forwardly of said motor on a transverse axis, friction clutch means and gear reduction driving mechanism for said drum rotatable on an axis forwardly of the latter, power connections from said motor to said friction clutch means including a gear carried on a shaft extending through said drum and upon which the latter is loosely mounted, reversing mechanism mounted on said shaft at one side of said drum, and means driven by said reversing mechanism for rotating the frame with respect to the base in opposite directions.

9. In a device of the class described, a base, a frame pivotally mounted on said base to swing in a horizontal plane, a boom and dipper mounted at the forward end of said frame, a motor at the rear end of said frame, a single strand flexible cable extending between said dipper and a drum mounted forwardly of said motor on a transverse axis, friction clutch means mounted forwardly of said drum, power connections from said motor to said friction clutch means including a gear carried on a shaft

- extending through said drum and upon which the latter is loosely mounted, reversing mechanism mounted on said shaft at one side of said drum, change speed mechanism connected with said reversing mechanism on the same side of the frame, and means driven from said change speed mechanism for rotating the frame on the base whereby the frame may be swung in opposite directions.
10. In a device of the class described, a frame having a boom, a dipper provided with a handle having rack and pinion connection on said boom, a motor at the rear end of said frame arranged on a transverse axis, flexible cable means for said dipper mounted on a transverse axis and centrally of said frame in front of said motor, means operatively connecting said motor and said drum including geared reduction mechanism and a friction clutch, and a second drum mounted forwardly of said first named drum having an independent friction clutch operatively connected with said gear reduction mechanism, flexible cable means connected with said second drum and extending to the boom for controlling the rack and pinion connection of the dipper handle and the boom, and means for propelling said base frame including a reversing mechanism and change speed transmission mounted on the frame at one side of the rope drums.
11. In a device of the class described, a base having traction means therefor, a frame pivotally mounted on said base to swing in a horizontal plane, a boom and dipper mounted at the forward end of said frame, a motor at the rear end of said frame, a single strand flexible cable extending between said dipper and a drum mounted forwardly of said motor on a transverse axis, friction clutch means mounted forwardly of said drum, power connections from said motor to said friction clutch means including a gear carried on a shaft extending through said drum and upon which the latter is loosely mounted, reversing mechanism mounted on said shaft at one side of said drum, change speed mechanism connected with said reversing mechanism, and means driven from said change speed mechanism both for rotating the frame on the base and for driving said traction means in opposite directions and at varying speeds.

Signed at Lima, Ohio, this 19th day of Feb., 1925.

JOHN D. RAUCH.

DISCLAIMER

1,569,031.—*John D. Rauch*, Lima, Ohio. POWER SHOVEL. Patent dated January 12, 1926. Disclaimer filed August 25, 1933, by the patentee, and the assignee, *The Ohio Power Shovel Company*.

Hereby enters this disclaimer to that part of the claim in said specification which is in the following words, to wit:

"5. In a device of the class described, a frame having a boom mounted at the forward end thereof, a dipper provided with a handle having a rack and pinion connected with said boom, a hydrocarbon motor at the rear end of said frame, flexible cable means connected to said dipper and extending over a sheave carried by said boom, a drum for said cable means mounted forwardly of said motor, a second drum at the front of said frame provided with flexible draft connection with said rack and pinion means to drive said means in opposite directions, and reversible power connection for said last named means."

[*Official Gazette September 19, 1933.*]
